DISPLAY DEVICE

William A. Lang, Webster Groves, Mo., assignor
to Monsanto Chemical Company, St. Louis,
Mo., a corporation of Delaware

Application December 31, 1949, Serial No. 136,371

5 Claims. (Cl. 217—11)

1

This invention relates to a display device. More specifically, this invention relates to a combined display device and shipping container, wherein merchandise to be displayed may be permanently or semi-permanently affixed for display purposes, and wherein the entire unit is so constructed as to serve as its own shipping container, eliminating on shipment the need for separate crating facilities.

In the merchandising of various commodities, it is quite a common practice to prepare display devices or containers wherein the merchandise to be advertised is affixed for display purposes. Such display devices after they have served their useful purpose in one location are then transported to another location for display purposes. Heretofore, display devices or containers so utilized have been generally of such a construction as to require on shipment additional crating or boxing to prevent damage to the display device in the course of shipment. In order to provide adequate protection for such display devices, extensive crating has usually been required in order that the display device does not become disfigured or marred to such an extent as to significantly diminish its eye appeal. Crating facilities, as heretofore required for the shipment of display devices, have been necessarily extensive and expensive in order to provide adequate protection for the display device. In addition to the expense involved, such need for individual crating of the display devices also has required the facilities and materials for crating the display devices, which materials may, at times, be almost as expensive as the materials with which the display device is constructed. Additional difficulties in the use of such a means of shipment of a display device have also been encountered on its receipt, since the uncrating and setting up of the crated display device necessarily causes considerable trouble and expense. It also has been frequently found that the area wherein the display device is uncrated becomes untidy and filled with debris necessitating quite extensive and expensive cleaning operations after the display device has been uncrated and assembled in its display position.

It is, therefore, an object of this invention to provide an improved display device.

It is another object of this invention to provide an improved combination display device and shipping container.

It is a further object of this invention to provide an improved combination display and shipping device which is so constructed that substantially all exposed surfaces which may become damaged or marred during shipment, are hidden from normal view when the device is assembled in its display position.

According to this invention, a combination dis-

2

play and shipping device is provided in which when assembled as a display device, substantially all exposed surfaces which have become marred or could become marred during shipment, are hidden from normal view. Furthermore, merchandise may be permanently affixed in the device of the invention. The device with its display merchandise may be compactly assembled to form a box-like package for shipping purposes.

10 The device in its shipping position does not require enclosure in a shipping crate to afford adequate protection. On reaching its destination, the display device may be reassembled for display. In view of the absence of a separate shipping crate or container, the debris which usually accompanies the unpackaging of such a device is eliminated.

In the drawings:

Fig. 1 is a perspective view of the display and shipping device assembled into its display position.

Fig. 2 is a perspective view of the display and shipping device partially assembled into its display position.

25 Fig. 3 is a side elevation of the two box-like elements of the device in position for assembly into their shipping position.

Fig. 4 is a fragmentary transverse section of the display device taken on line 4—4 of Fig. 1.

30 Fig. 5 is a fragmentary transverse section of the display device taken on line 5—5 of Fig. 2.

35 Before explaining in detail the apparatus of the present invention, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

40 Referring in detail to the drawings, the device of the invention comprises box-like members 1 and 2, which for convenience will be referred to hereinafter in the specification and claims as the shipping box and the display box respectively. However, it is to be understood that each box is in cooperative arrangement with the other whether the device as a whole is in its shipping or display positions.

45 Shipping box 1 which may be rectangular in shape is open at the front and is made up of top plate 3, bottom plate 4, side plates 5 and 6 and back plate 7.

50 Display box 2 which is also open at the front, is made up of top plate 8, bottom plate 9, side plates 10 and 11 and back plate 12. Top plate 8, bottom plate 9, side plates 10 and 11 and back plate 12 of box 2 are of such dimensions as to

55

permit box 2 to be inserted, open end first into box 1 until the outer surface of back plate 12 is flush with edges 13, 14, 15 and 16 of plates 3, 4, 5 and 6, respectively, of box 1 and the several edges of plate 12 are in close contact with the respective inner surfaces of plates 3, 4, 5 and 6.

Alternatively, back plate 12 may be of such a size as to cover edges 13, 14, 15 and 16 with its edges flush with the outer surfaces of plates 3, 4, 5 and 6. Preferably, however, in such an embodiment plate 12 does not extend so far as to cover edge 14 of plate 4 but only extends to the inner surface of plate 4. This provides a flat surface for resting the display box on the shipping box.

Side plates 10 and 11 of box 2 are recessed from the ends of base plate 9 to such an extent as to permit flaps 17 and 18, having rims 19 and 20, to be mounted at the extremities of base plate 9 in such a manner as to hang down from base plate 9 parallel with side plates 5 and 6 of box 1 when the device is positioned for display purposes and to be raised to a position parallel with side plates 10 and 11 when box 2 is prepared for insertion in box 1. Conveniently, flaps 17 and 18 may be attached by hinges 21 to base plate 9.

Rims 19 and 20 on flaps 17 and 18 are sufficiently wide to overlap and conceal edges 15 and 16 when flaps 17 and 18 are in a lowered position. It is to be noted that side plates 10 and 11 are sufficiently recessed on base plate 9 to permit flaps 17 and 18 to be mounted thereon in such a manner as to permit insertion of box 2 in box 1 when flaps 17 and 18 with rims 19 and 20 are in a raised position.

If desired, top plate 8 of display box 2 may be located somewhat below and parallel with the top edge of back plate 12 thereof. Such an arrangement provides an air space between plate 8 and plate 3 during shipment.

Flap 22 is attached to base plate 9 of box 2, for example by hinges 23 in such a manner that when the device is assembled for display purposes flap 22 hangs down either in a vertical position or at an angle thereby concealing most of edge 13 not concealed by rims 19 and 20. For shipping purposes flap 22 is rotated about hinge 23 to a vertical position. According to the embodiment in the drawing, side plates 10 and 11 are recessed sufficiently on base plate 9 to permit the hinged edge of flap 22 to rest on plate 9 when flap 22 is in a vertical position.

Top plate 8 of box 2 may have a different width, preferably smaller, as shown in the drawing, than base plate 9. The leading edges of side plates 10 and 11 of box 2 joining top plate 8 and base plate 9 may, as shown in the drawing, be irregular in configuration if desired.

In order to provide additional display space, box-like member 24 having a back plate 25, a base plate 26 and side plates 27 and 28 and attached, e. g. by hinges to top plate 8, may be provided. Side plates 27 and 28 may have such a configuration that leading edges 29 and 30 thereof form an extension of leading edges 31 and 32 of side plates 10 and 11. In the device shown in the drawing, edges 29 and 30 form a 45° angle to base plate 26 while the upper portion of edges 31 and 32 form a 45° angle with top plate 8. Consequently, when the device is in display position, edges 29 and 31 form a straight line as do edges 30 and 32 and when in shipping position, base plate 26 forms an extension of abbreviated top plate 8.

As a partial front plate for display box 2 and for decorative effect, member 33 may be attached to side plates 10 and 11 and top plate 8. Lights for illuminating the display may be mounted behind member 33 in a suitable manner.

Fig. 4 is a fragmentary transverse section in detail of the display device taken on line 4-4 of Fig. 1, showing one of two blocks 34 which are attached to display box 2 and positioned between display box 2 and shipping box 1 at each end thereof to raise the display box slightly and permit a block 35 to be partially inserted between box 1 and box 2 midway between the ends thereof, thereby governing the angle at which flap 22 is held, e. g. a 45° angle. Raising of box 2 by blocks 34 also facilitates the rotation of flaps 17 and 18. Shown in dotted lines in section in Fig. 4 is the position of flap 17 in its raised position. By pivotally mounting block 35 on plate 9 on pivot 36, it may be rotated entirely beneath box 2 for shipping purposes.

In Fig. 5 is shown a fragmentary transverse section in detail of the display device taken on line 5-5 of Fig. 2. Shown in dotted lines is flap 22 in section held at an angle as in Fig. 1 by a block 35 shown in section in dotted lines, partially inserted between box 1 and box 2.

The entire structure may be constructed of wood, and the like, and be conveniently assembled by the use of wood screws as shown in Figures 4 and 5. Piano type hinges 21 and 23 have been found particularly suitable for facilitating the rotating of all movable members. If desired, corners of the shipping box may be covered and protected by sheet metal.

Considering the functions performed by the various members of the display device of this invention when assembled in a display position, the outstanding utility of this novel display device is clearly evident. In assembling this device the following procedure is followed:

Display box 1 is removed from shipping box 2 and placed on top of shipping box 2 with the open end of box 1 directly above the open end of box 1. Flaps 17 and 18 of the upper portion of the display device are then lowered along the sides 5 and 6 and edges 15 and 16 respectively of box 2, and flap 22 is lowered over edge 13 thereby covering exposed areas of box 2 which could normally be viewable from the front and which may have become marred or damaged through shipment of the display device. Box 24 is then rotated in an upwardly direction so as to rest on the top of box 2, thereby providing for a display shelf at the very top of the unit. It is evident that substantially all surfaces of the display device in its assembled condition exposed during shipment and which would have been marred or damaged through shipment are either covered by movable members of the display device or face the back and are hidden from view, so that substantially all surfaces which are exposed to view from the usual front viewing position have never been exposed to the damaging treatment that would be obtained on shipment.

When shipping of the display device of this invention is desired, flaps 17 and 18 are raised and closed in about the upper portion 2 of the display device. Flap 22 is also raised to its upper position. Box 24 is rotated into its lower position. Box 2 of the display device is removed from its position on top of the lower portion 1 of the display device, and inserted open end first into box 1 of the display device. By means of

suitably located screws, it is rigidly held in place. Thus, the two boxes may be held together by screws passing through plates 3, 4, 5 and 6 and into the corresponding edges of plate 12. When the alternative embodiment is used in which plate 12 covers edges 13, 14, 15 and 16 or 13, 15 and 16, screws may be passed through plate 12 and into one or more of these edges. Shipping labels may then be attached or fastened to any of the thus exposed surfaces of the display device and the entire unit shipped without further crating or packaging. On reaching its destination, the device may again be set up as previously described with all surfaces damaged or marred in shipment being substantially hidden from view in its assembled display position. A particular advantage of the device of the invention is its relatively low weight in relation to the size and conveniently viewable location of the display area which is provided.

What is claimed is:

1. A combination display and shipping device comprising an open-ended shipping box and an open-ended display box of such a size as to be insertable within the shipping box, open end first, and adapted to be mounted on said shipping box when the device is in display position, said display box having flaps mounted on each side thereof and upwardly rotatable to a position parallel with and adjacent to the sides of the display box for shipping purposes and downwardly rotatable to a position parallel with and adjacent to the sides of the shipping box when the display box is mounted on the shipping box for display purposes, said flaps each having a rim extending lengthwise thereof and so positioned as to conceal the exposed edges of the side plates of the shipping box when the flaps are lowered, and said display box having a flap extending along the exposed edge of the lower plate of the display box and rotatably mounted thereon so as to conceal the exposed edge of the upper plate of the shipping box when in its lowered position.

2. A combination display and shipping device comprising an open-ended shipping box and an open-ended display box of such a size as to be insertable within the shipping box, open end first, and adapted to be mounted on said shipping box when the device is in display position, said display box having flaps mounted on each side thereof and upwardly rotatable to a position parallel with and adjacent to the sides of the display box for shipping purposes and downwardly rotatable to a position parallel with and adjacent to the sides of the shipping box when the display box is mounted on the shipping box for display purposes, a flap extending along the exposed edge of the lower plate of the display box and rotatably mounted thereon so as to conceal the exposed edge of the upper plate of the display box when in its lowered position, a rear plate of such a size as to correspond to the inside dimensions of the shipping box and a top plate narrower than the bottom plate thereof, said top plate having a second display box positioned thereon and rotatably attached to the leading edge of said top plate.

3. A combination display and shipping device comprising an open-ended shipping box and an open-ended display box of such a size as to be insertable within the shipping box, open end first, and adapted to be mounted on said shipping box when the device is in the display position, said

display box having flaps mounted on each side thereof and upwardly rotatable to a position parallel with and adjacent to the sides of the display box for shipping purposes and downwardly rotatable to a position parallel with and adjacent to the sides of the shipping box when the display box is mounted on the shipping box for display purposes, said flaps each having a rim extending lengthwise thereof and so positioned as to conceal the exposed edges of the side plates of the shipping box when the flaps are lowered.

4. A combination display and shipping device comprising an open-ended shipping box and an open-ended display box of such a size as to be insertable within the shipping box, open end first, and adapted to be mounted on said shipping box when the device is in display position, said display box having a rear plate of such a size as to correspond to the inside dimensions of the shipping box, and said display box having flaps mounted on each side thereof and upwardly rotatable to a position parallel with and adjacent to the sides of the display box for shipping purposes and downwardly rotatable to a position parallel with and adjacent to the sides of the shipping box when the display box is mounted on the shipping box for display purposes, said flaps each having a rim extending lengthwise thereof and so positioned as to conceal the exposed edges of the side plates of the shipping box when the flaps are lowered.

5. A combination display and shipping device comprising an open-ended shipping box and an open-ended display box of such a size as to be insertable within the shipping box, open end first, and adapted to be mounted on said shipping box when the device is in display position, said display box having a rear plate of a size such as to correspond to the inside dimensions of the shipping box, and said display box having flaps mounted on each side thereof and upwardly rotatable to a position parallel with and adjacent to the sides of the display box for shipping purposes and downwardly rotatable to a position parallel with and adjacent to the sides of the shipping box when the display box is mounted on the shipping box for display purposes, said flaps each having a rim extending lengthwise thereof and so positioned as to conceal the exposed edges of the side plates of the shipping box when the flaps are lowered, and said display box having a flap extending along the exposed edge of the lower plate of the display box and rotatably mounted thereon so as to conceal the exposed edge of the upper plate of the shipping box when in its lowered position.
